Specification for Design.

Patented Oct. 6, 1914.

Application filed August 7, 1914. Serial No. 855,707. Term of patent 3½ years.

To all whom it may concern:

Be it known that I, JAMES H. BOYE, a citizen of the United States, residing at Chicago, in the county of Cook and State of Illinois, have invented a new, original, and ornamental Design for a Combination Needle Threader and Sharpener, of which the following is a specification, reference being had to the accompanying drawing, forming a part hereof.

In the drawing, Figure 1 represents an

elevational view, and Fig. 2, a plan view of a combination needle-threader and sharpener in accordance with my new design.

I claim:

The ornamental design for a combination needle-threader and sharpener, as shown.

JAMES H. BOYE.
